ABSTRACT OF THE DISCLOSURE

New compound having cholesterol lowering activity. The compound has the formula,

wherein R is C₁₃—C₂₅ branched or straight saturated or unsaturated aliphatic group having OH or not, and R' is

The compound is prepared, for example, by reacting a fatty acid RCOOH with an amine

The present invention relates to cholesterol-lowering agents. More particularly, it relates to agents which are useful for the lowering of elevated levels of cholesterol in the blood.

Atherosclerosis, which is a form of simple intimal arteriosclerosis, is an adult disease for which there is no known satisfactory cure. Although the cause of atherosclerosis is not yet known, in spite of discussions in the academic world, it has broadly been recognised that one of the most significant histopathological manifestations of atherosclerosis is the deposition of lipids in the blood. Accordingly, research has been directed to the disturbed metabolism of lipids, and attention has been given to the extraordinarily elevated level of cholesterol in the blood.

A number of experimental and clinical facts have been reported which indicate the relationship between atherosclerosis and elevated blood cholesterol level. Hence, the development of agents to reduce the elevated blood cholesterol level is extremely important for the prevention of atherosclerosis.

Concentrated efforts have heretofore been made for the development of such agents for lowering cholesterol and

2

a number of compounds have been tested clinically, but none of them have proved to be completely satisfactory. Some are fairly effective but produce harmful side effects which are not negligible, and others have inadequate effectiveness, so that they require to be administered in large doses.

A group of compounds practically employed nowadays for the above purpose comprises unsaturated fatty acids, especially linoleic acid. The reason why linoleic acid is employed is because of its harmlessness to the human body. However, its effectiveness is not very high and it is uncertain and indefinite. Accordingly, large doses are required to obtain at least appreciable efficacy as a cholesterol-lowering agent.

10 We have found a group of compounds which are effective as cholesterol-lowering agents and are substantially non-toxic.

15 In accordance with this invention there is provided a cholesterol-lowering agent comprising an N-substituted 20 fatty acid amide having the formula,

25 wherein R is a C₁₃—C₂₅, branched or straight, saturated or unsaturated, synthetic or natural aliphatic chain having or not having OH group. Examples of RCO are the residues of following fatty acids, in the case of saturated acids,

30 myristic acid, palmitic acid, stearic acid, isostearic acid, arachidic acid, behenic acid, lignoceric acid, cerotic acid and montanic acid; and in the case of unsaturated acids, residues of tsuzuic acid, phytostoleic acid, myristoleic acid,

35 zoomaric acid, palmitoleic acid, petroselinic acid, oleic acid, elaidic acid, vaccenic acid, gadoleic acid, erucic acid, brasidic acid, selachloic acid, linoleic acid, linolenic acid, eleostearic acid, ricinoleic acid, parinaric acid, arachidonic acid, eicosatetraenoic acid, eicosapentaenoic acid, decosapentaenoic acid, hemp-seed oil fatty acid, linseed oil fatty acid, perilla oil fatty acid, styrax oil fatty acid,

40 oiticica oil fatty acid, kaya oil fatty acid, walnut oil fatty acid, poppy-seed oil fatty acid, safflower oil fatty acid, water melon-seed oil fatty acid, soybean oil fatty acid, sunflower oil fatty acid, rice bran oil fatty acid, pumpkin-seed oil fatty acid, kaoliang oil fatty acid, sesame oil fatty acid,

45 corn oil fatty acid, rape oil fatty acid, cottonseed oil fatty acid, olive oil fatty acid, cashew oil fatty acid, tsubaki oil fatty acid, ergot oil fatty acid, castor oil fatty acid, peanut oil fatty acid, palm oil fatty acid, palm kernel oil fatty acid, coconut oil fatty acid, beef tallow fatty acid, lard fatty acid, bone oil fatty acid, horse

50 fat fatty acid, locust oil fatty acid, crystalis oil fatty acid, shark oil fatty acid, cuttlefish oil fatty acid, sardine oil fatty acid, horse-mackerel oil fatty acid, mackerel oil fatty acid, saury pike oil fatty acid, herring oil fatty acid, saurel oil fatty acid, cod oil fatty acid, trout oil fatty acid, gray mullet oil fatty acid, tunny oil fatty acid, menuke oil fatty acid, menhaden oil fatty acid, flatfish oil fatty acid, eel oil fatty acid, various kinds of whole oil fatty acid, body oil fatty acid, skin oil fatty acid, head oil fatty acid, liver oil fatty acid, residual oil fatty acid and egg oil fatty acid

55 and the like vegetable, land or marine animal oils. In addition on thereto, double bond position isomers or stereoisomers thereof may also be used.

60 65 Of the above acids, the natural fatty acid residues may be, if desired, in the form of unsaturated fatty

acid residues which have been freed from saturated acid portions according to a suitable method such as, for example, cooling method, urea method, recrystallization method, metal salt method, distillation method or the like.

Next, R' in the aforesaid Formula I are as follows.

For the production of the present N-substituted acid amides may be used any of the processes known for the preparation of acid amides.

For example, (1) a fatty acid of the formula, is made RCOOH to react directly with an amine of the formula,

in the presence or absence of such dehydrating agent as a di-substituted carbodiimide compound, p-toluenesulfonic acid or p-toluenesulfonyl chloride or the like in an aqueous or organic solvent, (2) a fatty acid of the formula, RCOOH is converted to acid halide of the formula, RCOX, wherein X is a halogen atom, (Organic Synthesis, vol. 37, page 56) and the resulting acid chloride is brought into contact with at least an equimolar amount of the amine of the formula

in the presence of a basic condensing agent, (3) a lower alkyl ester or glyceride of a fatty acid of the formula, RCOOH is made to react directly with the amine of the formula,

in the presence or absence of a solvent and condensing agent or (4) a mixed acid anhydride of a fatty acid of the formula, RCOOH, having the formula,

wherein R'' is an alkyl or halogenoalkyl having 1 to 4 carbons, is made to react with the amine of the formula,

in the presence of a basic condensing catalyst, in the above (1) to (4) processes the R and R' is the same meanings as defined before. The processes (1) to (4) will be more fully explained below.

(1) (a) There have already been various researches wherein dicyclohexyl carbodiimide is used in synthesizing polypeptide. But there has never been a report that an amide is synthesized by using such higher fatty acid to produce an antiatherosclerosis agent, and therefore the process of the present invention is significant. Especially, the process of the present invention can be said to be very advantageous because of the fact that the desired product is readily isolated by filtering and separating the urea precipitated when the reaction has been completed, without any special operation and that the said urea can be used again after being regenerated by such treatment as dehydration.

For the di-substituted carbodiimide to be used in the process of the present invention, there may be exemplified dicyclohexylcarbodiimide, diisopropylcarbodiimide, diphenylcarbodiimide and any other dialkyl-, dicycalkyl- or di-substituted phenyl-carbodiimide. Any of them is equally useful in the process of the present invention.

In carrying out the process, a fatty acid, a corresponding amide and di-substituted carbodiimide, for example, are separately dissolved in an organic solvent, for example, such aromatic hydrocarbon organic solvent as benzene or toluene, such hydrocarbon solvent as n-hexane, cycloalkane, petroleum ether or gasoline, such ether solvent as dioxane, ether or tetrahydrofuran or such alkyl halide solvent as chloroform, ethylene dichloride or carbon tetrachloride or such ester solvent as methyl, ethyl propyl or butylacetate. These solutions are mixed at once at the room temperature or under cooling when heat generation is severe so as to be of about 1 in the mol ratio, and the mixture is stirred as required and is then allowed to stand at the room temperature for about 3 to 24 hours, whereupon the corresponding urea which is a by-product of the reaction will be precipitated. After the precipitate is filtered off, the desired product will be able to be obtained from the filtrate. Further, the excess di-substituted carbodiimide may be decomposed with acetic acid or the like as required.

The recovered urea is dehydrated and the resulting carbodiimide is usable again for the main reaction.

(b) The above-mentioned fatty acid and amine are dissolved in a suitable solvent such as, benzene, toluene, xylene, chloroform or carbon tetrachloride and the like. To the solution is added sulfuric acid, phenolsulfonic acid, p-toluenesulfonic acid, p-toluenesulfonylchloride, or an acidic or basic ion-exchange resin, e.g. IRA-400, IR-50 or IR-120 or Amberlist 15, 21, 26 or 27 as a dehydrating agent. Subsequently, the solution is heated using a water separator to separate and remove the water generated. Thereafter, the solvent is removed and the resultant is purified, whereby a desired product can be obtained in a high yield and in a simple manner. Alternatively, the desired object of the present process may sufficiently be achieved by merely heating the solution in the presence of a dehydrating agent, using as the solvent a tertiary organic amine such as pyridine, picoline or lutidine, besides the above-mentioned solvent.

(c) Thermal dehydration process.—The aforesaid fatty acid and amine are heated at about 130°-300° C. for several hours to several ten hours, if necessary in the presence of an acid catalyst such as boric acid, whereby a desired product is obtained. In this case, water generated may be removed out of the reaction system or the reaction can carry out in an autoclave to maintain the higher temperature.

(2) The reaction for condensing an organic amine with an acid halide is also known. However, so far as we know, there has been no report on the production of antiatherosclerosis agents by utilizing this process. We have found that, by using this process, an amide derivative which is

useful as an antiatherosclerosis agent can be obtained at a favorable yield under a mild nonoxidative condition.

Even when an excess of such basic condensing agent as such caustic alkali as caustic lithium soda or potash, such alkaline earth hydroxide as calcium or barium hydroxide, such alkali carbonate as lithium, sodium or potassium carbonate, such alkaline earth carbonate as calcium or barium carbonate, such tertiary amine as trimethylamine, dimethylaniline, pyridine, picoline, anion exchange resin or an excess of the starting amine or any of the above mentioned amines is used, the object of the invention will be able to be attained.

As for this solvent in this reaction, is used water, such organic ketone as acetone, methyl ethyl ketone or methyl isobutyl ketone, such ester as methyl acetate, ethyl acetate, propyl acetate or butyl acetate, such other as ethyl ether, propyl ether, tetrahydrofuran or dioxane, such hydrocarbon solvent as n-hexane, cyclohexane, benzene or toluene, such alkyl halide as ethylene dichloride, chloroform or carbon tetrachloride, such tertiary amine as dimethyl formamide, pyridine or picoline or any of the starting material amines as alone or as properly mixed.

Any temperature from the freezing point up to near the boiling point of the solvent used can be applied for the reaction. Further, it is desirable that the reaction is conducted in a stream of such inert gas as nitrogen or helium.

(3) Process using glycerides.—The aforesaid oil glyceride and an equimolar amount of an amine are mixed with a basic catalyst such as, sodium methylate, sodium ethylate, potassium butylate, potassium hydroxide or sodium hydroxide and the like, or with an acidic catalyst such as ammonium chloride or boric acid and the like, and the mixture is heated at about 50°-300° C. for 30 minutes to several ten hours to obtain a desired product. Even in the absence of the basic or acidic catalyst, the desired product can be obtained in a favorable yield when the amine is used in excess. In this case, the object can be achieved either in the presence or absence of an inert organic solvent.

(b) Process using esters.—An ester of the aforesaid fatty acid or of a fatty acid mixture obtained from the aforesaid oils or fats is mixed with an amine, and the mixture is heated at about 100°-300° C. for 30 minutes to several ten hours either in the presence or absence of the above-mentioned basic or acidic catalyst and of an inert solvent, whereby the object of the present process can be achieved. In this case, an alcohol formed may be removed out of the reaction system or an autoclave may be used.

The reactions of both processes (a) and (b) mentioned above should be done in an inert gas such as nitrogen to inhibit the formation of peroxides, coloring matters and the like undesirable by-products.

(4) The reaction of mixed anhydride method which is carried out at a low temperature is substantially complete at about 0° C. Unsaturated fatty acid derivatives, in particular, are unstable substances which, under certain conditions undergo oxidation, polymerization, position or geometrical isomerization and the like due to heat and air. Therefore, the process for producing unsaturated fatty acid amide derivatives according to the present invention, which is a low temperature reaction, has found a great significance to attain excellent results.

The solvents employed in the present reaction include ether, dioxane, tetrahydrofuran, dichloromethane, chloroform, carbon tetrachloride, methyl acetate, ethyl acetate, benzene, toluene, xylene, acetone and methylisobutylketone. As the basic materials, organic solvent-soluble tertiary amines such as trimethylamine, triethylamine, dimethylaniline, diethylaniline and pyridine and the like are desirably used. In some cases, however, inorganic bases, such as potassium carbonate and sodium carbonate, or basic ion exchange resins may also be used.

In order to prepare said mixed acid anhydride, lower alkyl haloformate having 1 to 4 carbon atoms in the lower

alkyl group is reacted with a fatty acid of the formula, RCOOH wherein R is the same meanings as identified above. Examples of the said lower alkyl haloformate include chloroformate.

The chloroformates to be employed are methyl chloroformate, ethyl chloroformate, and butyl chloroformate, and the like.

The effectiveness of the compounds was tested by using mice fed on a specific diet which was enriched with cholesterol and bile acids. The blood cholesterol level of the mice had been raised to 3 to 6 times as high as the normal level. The amide compound as well was mixed with the specific diet in an amount of 1%, and continuously administered orally for 8 to 12 days. Then the total cholesterol value in the blood serum of the animals was evaluated. During the tests, unfavourable side effects, such as the prevention of body weight gain and others, were not observed. It is noted that the stated compound is superior to linoleic acid. Moreover, in the linoleic acid-administered group, ineffective cases were sometimes observed due to the individual difference of the animals, and the effectiveness varied considerably even in the same individual animal. While, it should be emphasised that no such phenomena were observed in the linoleamide-administered group.

Another significant effect of the N-substituted acid-amide compounds according to the present invention is to prevent the deposition of cholesterol and fat in the liver, which occurs in animals fed on a diet rich in cholesterol. It seems that the linoleamide compounds improve the declined lipid-metabolism function of the liver. This effectiveness is also favourable, in view of the fact that the metabolism of lipid mainly relies upon the function of the liver. In the administration of linoleic acid, such effectiveness is never observed. The results are shown in Table 1.

The extremely low toxicities of the present linoleamide compounds are illustrated in Table 2, in which the acute toxicities of some of the present compounds in mice are listed.

TABLE 1

Material	Serum cholesterol, mg. percent	Liver cholesterol, mg./100 g.

NOTES:

- R¹=C₁₇H₃₁(linoleic acid residue)
 R²=Mackerel oil fatty acid residue.
 R³=Safflower oil fatty acid residue.
 R⁴=Sardine oil fatty acid residue.
 R⁵=Isostearic acid residue.

All the products involved in the present invention are novel compounds unknown to the literature.

As is seen from Table 2, no fatal case and no significant toxic symptoms were observed even in such large doses (per os) as 0.5 g. per 10 g., namely 50 g./kg. of the body weight. Also, no significant toxic symptoms, or fatal cases, were observed when the amides in amounts of 1%, 0.5%

ventional for oral administration. Thus, it may be enclosed in a capsule, or it may be in a liquid form, in a tablet form, or in a powder form. In preparing the agents in these various forms, the active compound may be mixed with or impregnated in a suitable solid carrier, or it may be mixed with a liquid carrier such as an edible oil, preferably those containing linoleic acid. It is also possible to use a mixture of two or more of the N-substituted amides of the invention. It may also be used as mixed with linoleic acid.

The present invention shall now be explained in detail with reference to the following examples which are given only for illustration and not for limitation of the invention in any way.

EXAMPLE 1

In 50 ml. of toluene 28 g. of linoleic acid and 12.9 g. of p-aminothioanisole were dissolved. To the solution was added a solution of 21 g. of dicyclohexyl carbodiimide in 20 ml. of toluene, and the mixed solution was allowed to stand overnight. The deposited crystals were removed by filtration, and the filtrate was washed successively with dilute alkali, dilute acid and water, and dried over anhydrous sodium sulfate and was then concentrated to obtain 28.3 g. of a desired product, M.P. 58°-60° C. (acetone).

Elementary analysis.—Calculated (percent): C, 74.81; H, 9.72; N, 3.49. Found (percent): C, 74.82; H, 9.98; N, 3.28.

EXAMPLES 2-9

Reactions were effected in the same manner as in Example 1 to obtain the results as shown in the following table:

EXAMPLE 10

In 100 ml. of toluene 28 g. of linoleic acid and 12.9 g. of p-aminothioanisole were dissolved. The solution was incorporated with 0.1 g. of p-toluenesulfonic acid and was then boiled for 16 hours using a water separator. The reaction mixture was washed successively with alkali, acid and water, was dried and concentrated and was then recrystallized from acetone to obtain 27.9 g. of a desired product, M.P. 58°-60° C.

Elementary analysis.—Calculated (percent): C, 74.81; H, 9.72; N, 3.49. Found (percent): C, 74.69; H, 9.88; N, 3.26.

EXAMPLES 11-14

Reactions were effected in the same manner as in Example 10 to obtain the results as shown in the following table:

Example No.	Acid	Amine	C, percent	H, percent		N, percent	
				Calc'd	Found	Calc'd	Found
11	Linoleic acid	<chem>CH2S-C6H4-NH2</chem>	49-51	74.81	74.66	9.72	9.81

Example 37

A mixture of 10 g. of linoleic acid and 6 g. of α -aminothiophenol was heated at 180° C. for 24 hours while removing water generated during the reaction. After completion of the reaction, the reaction product was immediately distilled to obtain 11.3 g. of a desired product, B.P. 203°-211° C./0.07 mm. Hg.

3.42.

Examples 38-67

Reactions were done in the same manner as in Example 37 to obtain the results as shown in the following table:

¹ Boric acid.

Example 68

A solution of 29.9 g. of linoleic acid chloride in ether was added dropwise at 0°-5° C. to a solution of 12.9 g. of p-aminothiophenol and 12.1 g. of dimethylaniline in ether. The mixed solution was heated at 60°-70° C. for 2 hours and was then allowed to stand overnight at room temperature. After separating insolubles by filtration, the reaction mixture was washed successively with dilute acid, dilute alkali and water, and was then dried and concentrated to obtain 30.2 g. of a desired product, M.P. 58°-60° C. (acetone).

Elementary analysis—Calculated (percent): C, 74.81;

H, 9.72; N, 3.49. Found (percent): C, 74.55; H, 9.89; N, 3.19.

Examples 69-74

Reactions were affected in the same manner as in Example 68 to obtain the results as shown in the following table:

In 50 ml. of anhydrous ether, 29.9 g. of linoleic acid chloride was dissolved. The solution was added dropwise to a mixture of 13.5 g. of o-aminothiophenol, 7 g. of trimethylamine and 100 ml. of anhydrous ether under cooling and stirring at 0°–5° C. After the addition, the reaction mixture was boiled for 2 hours to complete the reaction. The ether solution was washed successively with acid, alkali and water, dried and concentrated, and the residue was distilled to obtain 32 g. of a desired product, B.P. 200°–209° C./0.03 mm. Hg.

Elementary analysis.—Calculated (percent): C, 74.38;

H, 9.62; N, 3.61. Found (percent): C, 74.57; H, 9.82; N, 3.44.

Example 113

Example 107

A mixture of 8.8 g. of safflower oil and 5.9 g. of p-aminothioanisole was heated at 160° C. for 50 hours to obtain 10.3 g. of a desired product, M.P. 59°-73° C. (acetone).

Examples 108-112

Reactions were effected in the same manner as in Example 107 to obtain the results as shown in the following table:

A mixture of 8.8 g. of safflower oil, 4.7 g. of o-aniline-ethylthioether and 0.2 g. of sodium methylate was heated at 130° C. for 3 hours. The reaction mixture was dissolved in ether, and the solution was washed successively with dilute acid, dilute alkali and water and then dried and concentrated to obtain 8.9 g. of a desired product, M.P. 48°-62° C. (acetone).

Examples 114-117

Reactions were done in the same manner as in Example 113 to obtain the results as shown in the following table:

Ex. No.	Glyceride	Amine	Catalyst	Solvent	M.P., °C.
114	Cuttlefish oil		NaOC ₂ H ₅	Toluene	43-57
115	Saurel oil	Same as above	KOtBu		41-60
116	Mackerel oil		NaOC ₂ H ₅		46-66
117	Cod oil		NaOCH ₃	Xylene	37-52

Example No.	Glyceride	Amine	M.P., °C.
108	Linseed oil		38-46
109	Sunflower oil		52-61
110	Sesame oil		49-63
111	Olive oil	Same as above	61-69
112	Sardine oil		46-59

The fatty acid residues of amides obtained in the above reactions are isomers mainly having conjugated double bonds.

Example 118

A mixture of 29.4 g. of methyl linoleate and 19.3 g. of p-aminothioanisole was heated at 160° C. for 60 hours to obtain 32.1 g. of a desired product, M.P. 59°-62° C. (acetone).

Elementary analysis.—Calculated (percent): C, 74.81; H, 9.72; N, 3.49. Found (percent): C, 74.66; H, 9.91; N, 3.39.

Examples 119-127

Reactions were done in the same manner as in Example 118 to obtain the results as shown in the following table:

162	Residual oil		-----	200	72	184-215/0.03

Example 163

To a solution of 14 g. of linoleic acid and 5.5 g. of triethylamine in 100 cc. of tetrahydrofuran, 5.9 g. of ethyl chloroformate was added dropwise with stirring at -10° to -5° C. After the dropwise addition, the further stirring was continued at -5° C. for additional 20 minutes, and then 6.5 g. of O-SH-aniline was added dropwise at -5° C. Thereafter, the cooling of the reaction system was ceased and the stirring was continued until the temperature was elevated to room temperature. Subsequently, the temperature was gradually elevated and at 40° C., the reaction liquid was stirred for 20 minutes. After cooling the reaction liquid, tetrahydrofuran was removed by distillation under reduced pressure. The residue was dissolved in ether, and the solution was washed successively with cold dilute hydrochloric acid, cold aqueous sodium carbonate and water, and dried over anhydrous sodium carbonate.

After removal of the ether, the residue was distilled in vacuo to obtain 13.9 g. of a desired product, B.P. 210° – 215° C./0.02 mm. Hg, yield 64%.

Elementary analysis.—Calculated (percent): C, 74.38; H, 9.62; N, 3.61. Found (percent): C, 74.47; H, 9.61; N, 3.62.

Examples 164-198

In the same manner as in Example 163, 1 mole of a fatty acid and 1-1.1 moles of a basic substance are dissolved in 7-10 times the total amount of said materials of a solvent. To this solution, 1-1.1 moles of a chloroformate is added dropwise under stirring at -5° to -10° C. After the dropwise addition, the stirring is continued at said temperature for additional 10-30 minutes. Subsequently, 1-1.1 moles of an amine is added dropwise with stirring at said temperature. The reaction is substantially completed in about 10 minutes after the dropwise addition. In some cases, however, the temperature is elevated and the reaction liquid is stirred at room temperature and, if necessary, is heated to 40° – 50° C. Thereafter, the reaction liquid is subjected to ordinary treatments. According to the above procedures, the compounds shown in the following table can be obtained in 40-85% yields.

UNITED STATES PATENT OFFICE
CERTIFICATE OF CORRECTION

Patent No. 3,576,830

Dated April 27, 1971

Inventor(s) Toshitsugu FUKUMARU et al

It is certified that error appears in the above-identified patent and that said Letters Patent are hereby corrected as shown below:

Column 1, line 10, after the first Japanese application, the remaining five other Japanese applications should be listed as follows:

--674/67 filed December 27, 1966;
675/67 filed December 27, 1966;
568/67 filed December 28, 1966
43551/67 filed July 5, 1967; and
43552/67 filed July 5, 1967. ---.

Signed and sealed this 7th day of March 1972.
